(No Model.)

D. H. CHURCH.

DUST BAND FOR WATCHES.

No. 396,267.

Patented Jan. 15, 1889.

UNITED STATES PATENT OFFICE.

DUANE H. CHURCH, OF NEWTON, MASSACHUSETTS.

DUST-BAND FOR WATCHES.

SPECIFICATION forming part of Letters Patent No. 396,267, dated January 15, 1889.

Application filed June 23, 1888. Serial No. 277,988. (No model.)

To all whom it may concern:

Be it known that I, DUANE H. CHURCH, of Newton, in the county of Middlesex and State of Massachusetts, have invented certain new and useful Improvements in Dust-Bands for Watches, of which the following is a specification.

The time-trains of watch-movements, and particularly those portions constituting the escapement, are so delicate in construction that their proper and accurate action demands that they shall be free from disturbing influence. As ordinarily inclosed in cases of silver or gold for pocket use, it has been found almost impossible to exclude dust, and it frequently happens that quite large particles find their way through the joints of the case and lodge on some part of the movement.

It has been found practicable to protect the form of movement commonly known as the "full plate" by an encircling band of metal, which closes the space between the top and pillar plates and prevents access to the train. The construction of the form of movement known as the "three-quarter" plate is such that heretofore no effective way has been found to apply a dust-band thereto.

It is practically impossible to manufacture cases in quantities with the accuracy necessary to allow the pillar-plate of the watch-movement to rest upon the plate-shoulder of the case-center and the opposite flange of the case-center to make a practically dust-proof joint with the top (or smaller diameter) edge of the dust-band when the latter is made in the ordinary way. To do this would require absolute accuracy in distance between the plate-shoulder and the opposite flange of the case-center and in the width of the dust-band.

In full-plate movement and cases an opening at this place—viz., between the edge of dust-band and the flange of the case-center—is of little consequence if the top edge of the dust-band fits the top plate of the movement; but in three-quarter-plate movements such an opening renders the dust-band useless, as at some portion of the diameter the top plate is broken (as indicated by the technical name "three-quarter" plate) and the opening is directly into the space between the two plates of the movement.

The object of my invention is to provide a dust-band that shall be applicable to either of the above-named forms of movement, but more especially to the three-quarter plate, and shall not only serve to protect the sides or edge of a movement, but shall also close the space between the pillar-plate of the movement and the inwardly-projecting flange at the opposite side of the case-center.

My improved dust-band is so constructed as to enable it to adjust itself to the inevitable slight variations in cases, so that while the movement is held rigidly to one of the internal flanges of the case-center and rests on the "plate-shoulder" thereof the dust-band adjusts itself to the inner surface of the other flange of the case-center and insures a tight joint thereat, all of which I will now proceed to describe and claim.

Of the accompanying drawings, forming a part of this specification, Figure 1 represents a plan of a case-center containing a three-quarter-plate movement. Fig. 2 represents a section of the case-center, showing the movement as ordinarily mounted. Fig. 3 represents a similar section showing the application of my improved dust-band. Fig. 4 represents an enlargement of a part of Fig. 3. Fig. 4^a is a modification of the construction shown in Fig. 4. Fig. 5 represents a side view of a part of the dust-band. Fig. 6 represents a perspective view of the entire dust-band. Figs. 7, 8, 9, 10, and 11 represent modifications of the dust-band.

The same letters of reference indicate the same parts in all the figures.

In the drawings, *a* represents the top plate of a three-quarter-plate movement, and *b* represents the opposite or pillar plate, the latter having the usual outwardly-projecting shoulder, *b'*.

c represents the watch-case center, having the usual flange or seat, *c'*, for the shoulder *b'* of the pillar-plate, and the inwardly-projecting flange *d*, which bears against the margin of the top plate.

e represents the dust-band, which is a ring of comparatively thin sheet metal formed at one edge to inclose and closely fit the periphery of the pillar-plate above the shoulder *b'* thereof, and formed with an inwardly-pro-

jeeting beveled flange, e' , which contracts the diameter of its other edge nearly to that of the top plate.

To insure a close fit of the beveled or contracted edge of the dust-band against the flange d of the case-center, I provide means whereby continuous edgewise pressure is exerted on the dust-band to press the beveled portion thereof against the case-center flange.

10 Said pressure is best caused by springs h on the dust-band, arranged to bear on the pillar-plate, and thereby hold the beveled portion of the dust-band with a yielding pressure against the flange. Said springs are preferably integral with the dust-band and formed by cutting into the band, as shown in Figs. 5 and 6, to form tongues, and bending said tongues downwardly below the plane of the edge of the band that encircles the pillar-plate, the springs thus formed being thus adapted to bear on the shoulder b' of the pillar-plate. The springs h are so arranged that when the movement to which the dust-band is applied is being inserted in a case-center 25 the edge of the beveled flange e' comes in contact with the flange d of the case-center before the pillar-plate comes to a bearing on the seat c' , so that the springs are deflected from their normal positions and put under 30 tension when the movement is fully inserted; hence the springs thereafter exert a continuous edgewise pressure on the dust-band, whereby its beveled portion is kept in close contact with the flange d of the case-center.

35 In Fig. 4^a I have shown the under surface of the flange d as substantially flat or horizontal instead of beveled, as represented in the other figures.

In Figs. 7, 8, 9, and 10 I have shown the 40 springs formed by cutting vertical slits in the band and bending inwardly the angles formed by cutting said slits. The inwardly-bent portions constitute the springs and bear against a beveled seat, i , Fig. 7, formed on the pillar-plate. When the movement is inserted 45 in the case-center, the pressure of said springs against the beveled seat i tends to straighten out the springs, as shown in Fig. 7, and in their effort to resume their normal position 50 the springs, pressing inwardly on the inclined seat i , will force the dust-band upwardly against the flange.

Fig. 11 shows a spring, h , formed by cutting two vertical slits and bending inwardly 55 the tongue thus formed. The springs h may be made in separate pieces riveted or otherwise secured to the band e .

It is obvious that various other modifications in the form and arrangement of devices whereby the band is provided with an elastic 60 seating or bearing may be adopted without departing from the spirit of my invention.

I do not limit myself to the location of the elastic seating or bearing on the body of the band. A series of elastic springs may be secured to the case-center, and may rest, for example, on the inner surface of the flange c' , said springs being arranged to support the dust-band and press it against the flange d ; or a continuous yielding seat of rubber in the 70 form of a ring or washer may be applied to the case-center for the same purpose, although the last-named expedient would not be so desirable as those before described, on account of the liability of the rubber to deteriorate 75 and to tarnish the metal with which it comes in contact.

I claim—

1. A dust-band for watches, having an elastic 80 seating or bearing at one edge, whereby a yielding pressure is imparted to the band when it is incased, as set forth.

2. A dust-band for watches, having an elastic 85 seating or bearing at one edge and a beveled portion or flange at its other edge, as set forth.

3. A dust-band for watches, having elastic 90 tongues or springs at one edge, as set forth.

4. A dust-band for watches, having elastic 95 tongues or springs at one edge and a beveled surface or flange at the other edge, as set forth.

5. The combination of a watch-movement, a case having flanges $c' d$, a dust-band surrounding the movement between the flanges of the case, and means whereby an edgewise 95 pressure is imparted to the dust-band, as set forth.

6. The combination of a watch-movement, a case having flanges $c' d$, and a dust-band surrounding the movement between said flanges, 100 and provided at one edge with elastic bearings or springs and at the other edge with an inclined portion or flange, which is pressed by said springs against the case-flange, as set forth.

In testimony whereof I have signed my name to this specification, in the presence of two subscribing witnesses, this 20th day of June, A. D. 1888.

DUANE H. CHURCH.
